UNITED STATES PATENT OFFICE

HARRY K. CLEMONS, OF ST. PAUL, MINNESOTA

EXCAVATING, ELEVATING, AND LOADING MACHINE

Application filed August 3, 1927. Serial No. 210,306.

This invention relates to an excavating and dirt moving machine and particularly to such a machine which is drawn along the ground and removes a layer of dirt or earth, which 5 is loaded into the machine or into an adjacent vehicle. Such machines are commonly used in building and grading roads. It is desirable to have a machine which will load the dirt as it is removed from the road or surface being worked, so that the dirt can be transported at any desired distance.

It is an object of this invention, therefore, to provide a dirt removing and loading machine comprising a vehicle adapted to be drawn along the ground, having one or more 15 blades for removing the earth and having an elevating wheel adapted to receive the earth moved by said blades and elevating the same so that it may be discharged into the 20 vehicle.

It is another object of the invention to provide an excavating and loading machine comprising a vehicle adapted to be drawn along the ground and having a dirt receiving body, 25 an elevating wheel, means for removing the dirt from the surface worked into said wheel, together with means for directing the dirt from said wheel into said body or onto a conveyor carried by said body by means of which 30 it can be discharged into another vehicle.

It is still another object of the invention to provide an excavating and loading machine comprising a vehicle adapted to be drawn along the ground having a pair of 35 supporting wheels one of which is an elevating wheel into which the dirt is moved and elevated and having another wheel moving along the ground disposed adjacent to the side of said elevating wheel and forming a partial closure therefor, means preferably being provided for yieldingly holding said last 40 mentioned wheel in position.

It is a further object of the invention to provide an excavating, elevating and loading machine comprising a vehicle adapted to be drawn along the ground having an elevating wheel and a plurality of blades for removing the dirt from the surface worked and directing the same into said wheel, together 45 with means for adjusting said blades to vari-

ous positions and holding the same in said position.

It is still another object of the invention to provide an excavating, elevating and loading machine comprising a vehicle adapted to be drawn along the ground having an axle, a pair of supporting wheels, one of which forms an excavating wheel and is rigidly secured to said axle, the other wheel being arranged to be rigidly connected to said axle 55 or to move relatively thereto.

These and other objects and advantages of the invention will be fully set forth in the following description made in connection with the accompanying drawings, in which like reference characters refer to similar parts throughout the several views and in which,

Fig. 1 is a view in side elevation of the device;

Fig. 2 is a view in vertical section taken substantially on line 2—2 of Fig. 1;

Fig. 3 is a central vertical section through one of the wheels;

Fig. 4 is a view in side elevation of one of the wheels as seen from the left of Fig. 2;

Fig. 5 is a top plan view of the device, some portions being omitted;

Fig. 6 is a partial horizontal section, taken substantially on line 6—6 of Fig. 1, as indicated by the arrow; and

Fig. 7 is a horizontal section taken substantially on line 7—7 of Fig. 1, as indicated by the arrow.

Referring to the drawings, a machine is shown having supporting wheels 10 and 11. The wheel 11 is constructed and arranged as an elevating wheel, as later described, and said wheel has a hub portion 11a which is keyed to one end of axle 12, which axle extends through a tube 13 forming bearings for said axle, which tube 13 is rigidly carried in the sides 14a of a body member 14, which body member is thus carried on the axle and member 13. The tube 13 at one end projects into the recess in the inner end of hub 10a of the wheel 10, said wheel being normally journaled on the axle 12, said hub having clutch teeth 10b at one end forming a half clutch adapted to co-operate with a half

clutch member 15 slidable on the outer end of axle 12 and non-rotatably secured thereto by the pin 16 extending through said axle and a slot 15a in member 15. The member 15 has a circumferential groove 15b into which project pins 17 carried on a clutch fork lever 18, which lever is pivoted on the pivot 19 carried on a bracket 20 secured at one end to one side member 14a and also to a brace member 21 which is also secured to the side of the body 14. Lever 18 from pivot 19 extends inwardly at an angle toward body 14 and has the handle portion 18a which is flattened and disposed in a vertical plane and adapted to be held in engagement with any one of a plurality of teeth on a ratchet bar 22 projecting outwardly from the rear end of the body 14. It will be seen that movement of the end 18a of lever 18 will move the half clutch 15 longitudinally of axle 12.

The wheel 11 has the radially disposed spokes 11b bent at their outer ends and secured to the rim 11c, said spokes being alternately secured at their inner ends to opposite sides of the hub flange 11d. Inside of spokes 11b an annular flange or plate 11e extends about wheel 11. Another plate 11g of cylindrical form is disposed adjacent the inner edge of plate 11e, thus forming an annular trough 11h in wheel 11. The wheel 11 has secured about its rim within said trough a plurality of slightly curved plates 11f arranged in overlapping relation, as shown in Fig. 4 and riveted at their ends to the rim 11c.

A shaft 23 extends through and is secured in bearings 23b in sides 14a of the body, being adjustably held in place by the collar 23a thereon and a wheel 24 is journaled on the outer end of said shaft being urged away from the body by a coiled compression spring 25 surrounding shaft 23 and moving said wheel and shaft toward wheel 11 the position of wheel 24 being adjustable by adjustable stop collar 23a. The wheel 24 has a flat outer face which moves in close proximity to the inner edge of wheel 11, thus forming a partial closure for the trough 11h. A plate 26 is provided having its lower edge shaped to extend closely around the top portion of wheel 24 and said plate is yieldingly urged outwardly toward the side of wheel 11, by coiled compression springs 27 surrounding shafts 28, the inner ends of which are slidably mounted in bearings 29 secured to the side member 14a. The shafts 28 carry pins 30 projecting into slots 29a in the bearings 29, which pins limit the outward movement of shafts 28. Said shafts carry adjacent their outer ends the circular plates 31 which are pinned thereto and these plates have flat outer faces disposed adjacent the plate 26 or in contact therewith, the space between said outer faces and the edge of wheel 11 being slightly greater

than the thickness of plate 26. Plate 26 is bolted to the circular plates 31.

The body 14 has a bottom comprising hinged sections 14b hinged at their outer edges to the lower sides of the body and adapted to swing downwardly. Said sections are moved to closed position by chains 32 secured thereto and extending rearwardly where they are secure to a shaft 33 rotatably mounted in the sides 14a and provided with a ratchet wheel 34 at one end, with which cooperates an actuating pawl 35 carried on a lever 36 pivoted on shaft 33. A stop dog or pawl 37 also co-operates with ratchet wheel 34. Said body has a rear wall 14c and a step 80 platform 14d extends rearwardly from the rear end of said body. Bars 38, shown as in the form of angle bars, project forwardly from the front end of the body, being secured in any pair of a plurality of holes 39a in transverse bars 39 disposed at the front of the body and forming part of the frame thereof. Bars 38 having plates 40 of arcuate shape are secured thereto in spaced relation forming a guiding and supporting means for a ring plate 41, which plate has bearings 41a secured thereto in which are journaled the trunnions of a castor wheel 42. The bearings 41a are engaged by the ends of a fork member 43, the sides of which project forwardly and have secured therebetween at their forward ends the clevis 44 to which the traction means for the device will be attached.

A plurality of blades are provided for removing dirt from the surface worked and directing the same to the wheel 11, and while the number of these blades and the arrangement thereof may be varied, in the embodiment of the invention illustrated, two of said blades 45 and 46 are shown. The blade 45 is carried on bars 47 secured to the rear side thereof by the clamping member 48, said bars extending forwardly and being secured together by the plate 49 and having their front ends pivoted on pivot 50 carried in plates 51 depending from the under side of the forward member 39. Bars 47 have the rods 52 secured thereto, the upper ends of which are secured to sleeves 53, which sleeves have longitudinally extending slots 53a therethrough. Rods 54 extend into the sleeves 53 and have lateral extensions or pins 54a thereon extending into the slots 53a. The upper ends of rods 54 are adapted to be engaged in any pair of a plurality of holes 55a formed in the end of a lever 55, pivoted in a bracket 56 secured to the front of body 14 which lever has a pawl thereon adapted to seat in any one of a plurality of notches 57a formed on a segmental bracket 57 secured to a bar 14e, which extends along the side of the front wall of the body 14. The pawl on lever 55 is actuated by the usual pawl handle 58. Collars 59 are secured to the rods 530

54 above sleeves 53 and coiled springs 60 surround said rods and are disposed between collars 59 and the upper ends of sleeves 53. The blade 46 has bars 61 secured to its rear side which are secured together at their forward ends and pivoted to one of the side members 14f of the body frame by the pivot 62. The bars 61 and rods 63 are secured to the sleeves 64 and rods 65 extend into the upper ends of said sleeves and have extensions projecting (said projections not shown) into slots similar to the projections 54a on rods 54. The rods 65 are secured in one pair of a plurality of holes 66a formed in a lever 66 which is rotatably mounted on the sleeve 13 and provided with a series of teeth 66b at its upper edge with which meshes a worm gear 67 secured to shaft 68 journaled in bearings 69 secured to the side 14a of the body, shaft 68 extending rearwardly and having a crank portion or handle 68a at its rear end disposed at one side and above the step platform 14d. The rods 65 have collars 70 secured thereto and coiled springs 71 are disposed between said collars and the upper ends of sleeves 64.

An endless conveyor 72 is provided comprising an endless sheet of flexible material moving over rollers carried respectively on shafts 73 and 74, the latter being mounted in brackets 75 secured to the conveyor frame 72a, which carries bearings 72b pivoted by the pivot 76 to the members 14e, one of which is disposed at either side of the body. The shaft 73 is carried in bearings 77 secured to the inner side of the side members 14a and has a sprocket wheel 78 secured to its outer end over which runs a chain 79. Chain 79 also runs over a sprocket member 80 journaled on the sleeve 13 which sprocket is in the form of a half clutch adapted to engage with the half clutch 10c formed on the inner end of the hub 10a of wheel 10. The member 80 is provided with a circumferential groove 80a engaged by the end of a clutch fork lever 81 pivoted at 82 to a bar projecting from the body and having its rear end provided with a handle portion 81a adapted to be held in engagement with any one of a series of ratchet teeth on a ratchet bar 83 secured to the body 14. The conveyor frame has a downwardly extending bracket 86 on its bottom having a plurality of holes therein through one of which passes a pin 87 also adapted to pass through any one of a plurality of holes formed in a bar 88 pivoted on the pivot of lever 55. With this construction the conveyor 72 may be tilted about pivot 76, it being understood that the chain 79 will have to be lengthened or shortened accordingly. A deflecting member 84 extends with its inner end in a forwardly inclined direction and projects into the trough 11h, said deflector having a triangular-shaped inner bottom portion or flange 84a and being sup-

ported on the member 85 secured to one of the side members 14a.

In operation the machine will be drawn along the ground by suitable traction means connected to clevis 44. The plates 45 and 46 will be adjusted to the desired height by means of lever 55 and crank 68a respectively and the bottom sections 14b of the body will be in closed position, as shown in Fig. 2. If it is desired to load the dirt into the body 14 the rear end of conveyor 72 will be raised above the deflecting means 84, said member being moved for this purpose. As the machine advances along the ground the blade 45 will scrape off or excavate a layer of earth which will be directed to the inner end of said blade due to the inclination thereof and this dirt will be engaged by the blade 46. This may move at a lower level and excavate further dirt. The earth from blade 46 will be moved outwardly and directed into the trough 11h of wheel 11. As the wheel advances its rear side will move upwardly and the dirt will be carried upwardly in said wheel along the side of wheel 24, which will roll in contact with the ground and assist in moving said earth. The earth, dirt, etc., move upward in the wheel being retained therein by the plate 26 and is eventually scraped from and deflected out of the wheel by member 84, said member directing the dirt inwardly over member 85 and bottom member 84a into the body 14. When the body 14 has been filled with dirt the blades 45 and 46 may be raised and the vehicle taken to the desired place where the dirt can be dumped by rotating shaft 33 by the ratchet lever 36. Pawl 37 will be disengaged and the weight of the dirt will usually rotate shaft 33 and the bottom sections 14b will drop downwardly and the dirt is thus dumped. The bottom may again be closed by manipulation of lever 36 after which pawl 37 will be again engaged with ratchet 34. The springs 60 and 71 yieldingly hold the blades 45 and 46 down in operative position but will yield as said blades are moved upwardly by the shock of encountering a stone or other hard object. It will be seen that the plates 11f greatly strengthen the rim 11c of wheel 11 and the exposed edges of said plates also assist in moving the dirt upwardly. The wheel is thus kept from getting into elliptical form. If it is desired to move the dirt into another vehicle the conveyor 72 will be adjusted so that its rear end is beneath the deflecting member 84 and the dirt deflected from wheel 11 will then be discharged on the conveyor. Lever 81 will be moved to engage the half clutch 80 with hub 10a. The chain 79 will then be driven by rotation of wheel 10 and the conveyor will be moved to convey the excavated material forwardly where it may be discharged into the body of a vehicle immediately in front of the ma-

70

chine. It will be seen that by moving lever 18 clutch member 15 may be connected to the hub 10a and the wheel 10 will then be rigidly connected to axle 12 so that both wheels will turn with the axle and assist in handling the dirt. The wheel 24 and plate 26 are yieldingly held in close proximity to wheel 11 and may thus move away from said wheel if great pressure is exerted thereon or 10 a stone should become jammed in the wheel 11. The machine can be effectively steered by the castor wheel 42 which can be rotated on its plate 41 and the line of draft shifted laterally by adjustment of members 38.

15 From the above description it is seen that applicant has provided a very efficient machine for excavating, elevating, transporting and loading excavated material. The parts of the machine are all visible and the manipulating elements are conveniently arranged for operation. The blades or plows are yieldingly mounted and these can be turned to various positions by having the ends of the bars 47 or 61 extend more or less into the clamps 20 at the rear of the blades. The wheel 24 and plate 26 are mounted for yielding movement under extreme strain. The double blade or plow system is very useful on road work, one blade acting to cut down the banks ahead of 25 the wheel 11 and direct the plowed material to the second blade. The blades can be used independently or simultaneously, as desired. Both of the wheels can be used to drive the conveyor by connecting the wheel 10 to 30 the axle 12. The conveyor can be moved to operative or inoperative position. An effective draft is always possible on the machine owing to the swivel castor wheel 42.

It will, of course, be understood that various changes may be made in the form, details, 40 arrangement and proportions of the parts without departing from the scope of applicant's invention, which, generally stated, consists in a device capable of carrying out the objects above set forth and novel parts and combination of parts disclosed and defined in the appended claims.

What is claimed is:

1. In a machine of the class described, a 50 vehicle having a body adapted to be drawn along the ground, a pair of wheels supporting said body, one of said wheels being constructed and arranged to form an elevating means, an axle supported by said body to 55 which said last mentioned wheel is secured, the other of said pair of wheels being journaled on said axle, and means for connecting and disconnecting said last mentioned wheel to said axle.

60 2. In a machine of the class described, a vehicle having a body adapted to be drawn along the ground, a pair of wheels supporting said body, one of said wheels being constructed and arranged to form an elevating means, an axle to which said last mentioned 65

wheel is secured, a sleeve extending through and supported by said body in which said axle is journaled, the other of said wheels being journaled on said axle and clutch means at the outer side of said other wheel 70 for connecting and disconnecting the same and said axle.

3. In a machine of the class described, a vehicle having a pair of supporting wheels and adapted to be drawn along the ground, 75 one of said wheels having an annular trough formed therein open at its inner side constituting an elevating means, an auxiliary wheel having a flat outer surface disposed in close proximity to the inner side of said wheel, and resilient means urging said auxiliary wheel toward said first mentioned wheel.

4. The structure set forth in claim 3, a plate disposed above said auxiliary wheel 85 and fitting about the upper portion thereof, and resilient means for moving said plate outwardly in close proximity to the inner side of said first mentioned wheel, said auxiliary wheel and said plate forming a closure for said trough.

5. In a machine of the class described, an elevating wheel comprising a rim, an annular cylindrical member disposed within said rim, a plate at the side of said member forming a trough between said rim and member, and a plurality of slightly curved plates disposed inside of said rim in overlapping relation and secured thereto.

6. In a machine of the class described, a 100 pair of supporting wheels, one of which is constructed and arranged as an elevating wheel, an axle to which said wheel is secured, said other wheel being journaled on said axle and having a hub with a half 105 clutch formed at each end, means secured to said axle comprising a half clutch adapted to be moved into engagement with said hub to connect said hub and axle, a conveyor adapted to receive material from said elevating wheel, driving means for said conveyor comprising a member forming a half 110 clutch slidable on said axle, and means for moving said last mentioned member into and out of engagement with said hub of said second mentioned wheel.

7. An elevating wheel for an excavating machine having a bearing rim, a plurality of trussing and supporting plates secured to the inner side of said rim in over-lapped 115 relation, said plates assisting in the elevation of material in said wheel.

8. A machine of the class described having in combination a vehicle having a body adapted to be drawn along the ground, a 125 pair of wheels supporting said vehicle, one of which is constructed and arranged as an elevating wheel and is movable about a substantially horizontal axis, a blade disposed in front of said wheel to excavate material 130

from the path thereof and deliver the same at one side of said wheel and a second blade disposed in the rear of said first mentioned blade and receiving therefrom and disposed at a lower level than said first mentioned blade and at the side of said wheel in a position to direct material thereto.

9. A machine of the class described having in combination a vehicle having a body adapted to be drawn along the ground, an axle carried by said body, a pair of wheels supporting said axle, one of which is constructed and arranged as an elevating wheel and is movable about a substantially horizontal axis, said wheel having elevating means on its inner side, an adjustable blade disposed in front of said wheel to excavate material from the path of said wheel and being inclined to direct said material toward the inner side of said wheel, a second blade inclined in a direction opposite to said first mentioned blade and adapted to receive material therefrom and direct the same outwardly toward said wheel.

25 In testimony whereof I affix my signature.
HARRY K. CLEMONS.
